UNITED STATES PATENT OFFICE.

FREDERICK A. APFELBAUM, OF NEW YORK, N. Y.

LANTERN-SLIDE.

1,132,423.

Specification of Letters Patent. Patented Mar. 16, 1915.

Application filed August 26, 1914. Serial No. 858,660.

To all whom it may concern:

Be it known that I, FREDERICK A. APFELBAUM, a citizen of the United States, and a resident of the city of New York, borough 5 of Manhattan, county and State of New York, have invented a new and Improved Lantern-Slide, of which the following is a full, clear, and exact description.

Among the principal objects which the 10 present invention has in view are: to provide slides of the character mentioned with manually adjustable means for showing the time of day on the illuminated field of the screen used for exhibiting said slides; to 15 provide a simple and efficient means for adjusting the hands used in conjunction with a clock dial for announcing the time periods; to perform the operation of mounting said hands for use in conjunction with the dial in 20 a manner to avoid destruction or damage to the said dial or element carrying same.

Drawings.—Figure 1 is a face view of a slide constructed and arranged in accordance with the present invention; Fig. 2 is a face 25 view of the color plate used in the manufacture of said slide; Fig. 3 is a face view of a cover plate used in conjunction with the color plate to protect the same; Fig. 4 is a vertical section on a large scale taken as on 30 the line 4—4 in Fig. 1.

As seen in the accompanying drawings, a color plate 8 and a cover plate 9, both constructed of glass, or other suitable transparent material, are used in conjunction and 35 mounted by means of edge binding tape 10. In the present invention the plates 8 and 9 are maintained in spaced relation by filling strips 11 which are placed between the plates adjacent to the edges thereof and surrounding the transparent field of the said plates. In producing the color plate 8 the photographic emulsion is placed on one side thereof and the plate is exposed, using for that purpose a negative arranged to print a clock 40 dial such as shown in Figs. 1 and 2, and designated by the numeral 12. The remainder of the field or transparency is printed to show amusement pictures, or advertising matter.

50 After the plate 8 has been photographically developed the cover plate 9 is placed thereover, the filling strips 11 being first adjusted to support the said plate. The thickness of the strips 11 corresponds to the thick-

ness of the overturned head of the rivet 13. 55 The rivet 13 is placed in a hole bored in the plate 9 to correspond with the center spot 14 of the dial 12. The outer end of the rivet 13 is curled over the hour hand 15 to hold the said hour hand and the minute hand 16 in 60 operative position, exercising thereon just sufficient pressure to maintain said hands in the positions to which they are moved by the operator. The hands 15 and 16 in service are disposed at the outer side of the plate 9 65 to be readily accessible for adjustment by the operator.

It is obvious that if the plate 9 be broken as a result of the boring of the hole to receive the rivet 13, the loss incident thereto is relatively slight as compared with that incurred if the hole is bored in the color plate 8, which method of construction is involved in the manufacture of plates made in accordance with the patent granted to Meinhardt February 6, 1912, #1,016,575; also it is obvious that the strength of the color plate 8 is not impaired when constructed in accordance with the present invention; also the setting of the two hands 15 and 16 is accomplished 70 in a more natural or conventional way than provided for in the above mentioned patent, in the present instance both of the hands being adjusted to announce the hour and minute or "time" by moving the hands independently and manually over the cover plate 9 to register with the markings on the dial 12 of the color plate 8. 80

Claims:

1. A slide comprising a color plate having 90 a time dial imprinted on one surface thereof; a transparent cover plate mounted in fixed relation to said color plate; and a plurality of clock hands pivotally mounted on said cover plate, the pivot of said hands being coincident with the center of said dial. 95

2. A slide comprising a color plate having a time dial imprinted on one surface thereof; a transparent cover plate mounted in fixed relation to said color plate; and a plurality of clock hands pivotally mounted on said cover plate, the pivotal axes of said hands being coincident with the center of said dial, said hands extending from the exposed side of said cover plate, for manually 100 shifting said hands. 105

3. A slide comprising a color plate having a time dial on one surface thereof; a trans-

parent, protective cover plate mounted in fixed relation to said color plate; and movable indicating members pivotally mounted on said cover plate, said members being manually manipulated for indicating time periods in conjunction with said dial.

In testimony whereof I have signed my

name to this specification in the presence of two subscribing witnesses.

FREDERICK A. APFELBAUM.
